UNITED STATES PATENT OFFICE.

ZANON V. KUCHAN, OF ABERDEEN, WASHINGTON.

RAILROAD-TIE.

1,319,010.

Specification of Letters Patent. Patented Oct. 14, 1919.

Application filed March 26, 1919. Serial No. 285,212.

To all whom it may concern:

Be it known that I, ZANON V. KUCHAN, a citizen of the United States, residing at Aberdeen, in the county of Grays Harbor 5 and State of Washington, have invented certain new and useful Improvements in Railroad-Ties; and I do hereby declare the following to be a full, clear, and exact description of the invention, such as will enable 10 others skilled in the art to which it appertains to make and use the same.

This invention relates to railroad ties and fasteners and the primary object of the invention is to provide a tie formed from 15 steel or the like to replace the ordinary wooden tie, and thereby dispense with the inconveniences usually associated therewith.

Another object of the invention is to provide an improved steel railroad tie, having 20 means whereby the rails can be attached thereto, without the use of spikes or other fastening elements.

A further object of the invention is to construct an improved steel railroad tie for 25 receiving the terminals of a pair of rail sections and locking the same against movement in relation to each other and to the tie.

A further object of the invention is to provide an improved railroad tie of comparatively light weight, so that the same 30 can be readily handled and transported, without weakening the same.

A still further object of the invention is to provide an improved device of the above 35 character, which is durable and efficient in use, one that is simple and easy to manufacture, and one that can be placed upon the market at a reasonable cost.

With these and other objects in view, the 40 invention consists in the novel construction, arrangement and formation of parts, as will be hereinafter more specifically described, claimed and illustrated in the accompanying drawings, forming a part thereof, in 45 which:

Figure 1 is a plan view of a portion of a railroad track constructed in accordance with my invention,

Fig. 2 is a perspective view of one of the 50 ties,

Fig. 3 is a longitudinal section taken on the line 3—3 of Fig. 1,

Fig. 4 is a horizontal longitudinal section taken on the line 4—4 of Fig. 3,

Fig. 5 is a longitudinal section taken on 55 the line 5—5 of Fig. 1,

Fig. 6 is a detail cross section taken on the line 6—6 of Fig. 1,

Fig. 7 is a perspective view of one of the 60 locking wedges,

Fig. 8 is a perspective view of the locking bar, and

Fig. 9 is a detail perspective view of one 65 end of the rail.

Fig. 10 is a detail perspective view of one 70 of the ties positioned intermediate the meeting terminals of the rails.

Referring to the drawings in detail, wherein similar reference characters designate corresponding parts throughout the 75 several views, the numeral 1 generally indicates a railroad track including ties 2 and rails 3. The ties 2 are formed from steel or the like and each includes a hollow body 4 having an upper wall 5, a bottom wall 6, 80 and side walls 7. The side walls are cut away intermediate the ends thereof and the upper wall 5 has its side edges cut inwardly as at 9 at the cutout portion of the side walls. The bottom wall 6 is likewise provided with an opening 10. This construction provides a steel tie of exceedingly light weight, which reduces the cost of manufacture and permits the ties to be more readily handled. The upper wall 5 of each tie is 85 formed relatively thicker, as at 11, at each end thereof for receiving the rails 3 and vertical and diagonal braces are arranged under the thickened portion and form additional means for supporting the rails.

Each thickened portion of the ties is provided with transversely extending grooves 13 having one wall thereof undercut as at 14 to conform to the configuration of the base flange of the rail 3, for receiving the 95 same, when the rails are placed in position. The lower wall 15 of the groove is formed comparatively flat, so as to form a seat for the base of the rail 3. A second groove 16 extends transversely of each thickened portion 11 of the ties opposite to the undercut portion 14 and extends below the lower wall 15 of the groove. The side wall 17 of the groove 16 opposite to the undercut portion 100

14 is also undercut, as clearly shown in the drawings, and the same forms a retaining shoulder 18 for the wedge members 19. The wall 17, as shown, is inclined from one 5 end toward the other end to conform to the configuration of the wedge members 19.

Each of the wedge members 19 includes a base 20 having a flange 21 formed at one longitudinal edge thereof for engaging the 10 base flange of the rail opposite to the wall 14 and the same has the lower surface 22 thereof inclined to conform to the configuration thereof. The opposite edge is inclined from one end to the other, as shown at 23, 15 so that when the same is driven into the groove 16 the same will have a wedging effect and can only be removed from or inserted in one end of the groove. The upper surface of the wedge 19 has the longitudinal 20 edge thereof opposite to the flange 21 cut away, as at 24, so that the same can readily fit into the cutout portion of the wall 17. The base 20 is adapted to engage the side walls of the groove 16 and the flange 21 25 thereof is adapted to overlie the base 15 of the groove 13, so as to coöperate with the undercut portion of the wall 14 to engage the base flanges of the rail and retain the same in position against displacement.

30 It can be seen that the rail 3 is first placed in the groove 13 with one of the base flanges thereof positioned in the undercut portion of the wall 14 and the wedge member 19 is then driven into place and the flange 21 35 thereof engages the opposite base flange of the rail and holds the same against displacement. A key 25 is provided for locking the wedge members 19 in place against accidental movement with relation to the 40 tie and rails which is adapted to fit into alined grooves 26 and 27 formed in the upper edge of the tie and wedge members respectively. The side walls of the groove 26 are provided with undercut portions 28, 45 for a purpose which will hereinafter more fully appear. A groove 29 extends transversely of the groove 26 and communicates therewith and the under cut portions of the wall 28, for a purpose which will hereinafter more fully appear. The key 25 includes a substantially rectangular body, having 50 outstanding lugs or ears 31 formed on the side edges thereof at one end thereof and the opposite end is provided with an up- 55 standing lug 32, which forms a handle for the key, whereby the same may be readily grasped.

When the wedges 19 are placed in position and the grooves 26 and 27 aline, the key 60 25 is operated so as to force the ears 31 in the transverse slot 29 and the key is then pushed so as to slide the ears 31 in the cutout portions of the walls 28 of the slot 26 and when the same have reached the end 65 walls thereof the key is then thrown down-

wardly so as to lie in the slot 27, which locks the wedges in position and effectually holds the same against displacement.

As clearly shown in the drawings, one of the wedges engages the outer side of the 70 rail while the opposite wedge engages the inner side of the opposite rail.

Certain of the ties designated by the numeral 35 are arranged to receive the terminals of the rails 3 and to form a joint for the 75 same, so as to prevent displacement thereof. These ties 35 are constructed exactly as the ties 2, with the exception that the walls 16 of the groove 13, which forms a rest for the bases of the rails, are provided with pairs 80 of spaced upstanding lugs 36, which are adapted to fit in notches 37 formed in the side edges of the terminals of the rails, which effectively hold the rail sections against longitudinal movement in relation 85 to the tie.

From the foregoing description it can be seen that an improved metallic tie is provided, which effectively holds the rails in position and also forms joints for the same, 90 without the use of spikes or nuts and bolts.

In practice, I have found that the form of my invention illustrated in the accompanying drawings and referred to in the above description, as the preferred embodiment, 95 is the most efficient and practical; yet realizing the conditions concurrent with the adoption of my device will necessarily vary, I desire to emphasize that various minor changes in details of construction, proportion and arrangement of parts may be resorted to, when required, without sacrificing any of the advantages of my invention as set forth.

What I claim as new is:

1. A metallic railroad tie having rail seats formed therein, said tie having grooves formed therein adjacent to said rail seats, sliding wedges fitted in said grooves, said wedges having flanges formed thereon and 110 arranged to engage the base flanges of the rail, and a locking key slidably and pivotally carried by the tie and adapted to engage each wedge, as and for the purpose specified.

2. A metallic railroad tie having rail seats formed in the upper side thereof, grooves formed in the upper basis of the tie adjacent to said rail seats, flanges overhanging said grooves, sliding wedges fitted in said grooves and arranged to engage the base flanges of a rail, said ties and wedges having slots formed therein and arranged to aline when the wedges are in operative position, and a sliding key arranged to fit in said grooves 120 to hold the wedges against accidental movement, as and for the purpose specified.

3. A metallic railroad tie having rail seats formed therein, a sliding wedge carried by the tie and arranged to engage a rail posi- 125

tioned in said seat, slots formed in the tie and wedges and arranged to aline with each other when the wedges are in operative position, the slots in the ties having the side 5 walls thereof provided with grooves, and a key arranged to slidably fit in the slots in the tie and fit in the slot in the wedge to hold the same against displacement, said key having outstanding ears formed on the

side walls thereof and arranged to engage 10 the grooves formed in the side walls of the slots formed in the ties.

In testimony whereof I affix my signature in presence of two witnesses.

ZANON V. KUCHAN.

Witnesses:

ANDREW GUDAZ,
JOHN RONOLICH.
